[57] CLAIM

The ornamental design for a faucet, as shown and described.

DESCRIPTION

FIG. 1 is a perspective view taken from the top, front and left side of faucet showing our new design;

FIG. 2 is a right side elevational view thereof, the left side being a mirror image of the right side shown;

FIG. 3 is a front elevational view thereof;

FIG. 4 is a rear elevational view thereof;

FIG. 5 is a top plan view thereof; and

FIG. 6 is a bottom plan view thereof.

FIG.1

FIG. 2

FIG.3
